UNITED STATES PATENT OFFICE.

ARTHUR L. WILSON, OF HAMMOND, INDIANA, ASSIGNOR TO WESTINGHOUSE ELECTRIC & MANUFACTURING COMPANY, A CORPORATION OF PENNSYLVANIA.

HIGH-SPEED RADIOTRANSMITTER.

Application filed December 13, 1922. Serial No. 606,558.

My invention relates to control systems, having particular relation to high-speed automatic radio transmission systems.

The principal object of my invention is to provide a system of the class described, wherein relatively slow-speed circuit-interrupting devices designed to handle heavy currents and high voltages are employed, the signaling speed of the combination of devices being greater than that of a single interrupting device alone.

In the present state of the art, the relays employed in the usual signal-control systems are required to control relatively heavy currents of high voltages, thereby necessitating the use of extremely rugged relays having large braking distances. Such relays, by reason of the heavy construction of the moving parts, are inherently slow in operation and thus are unadapted for high-speed signal-control systems.

I have found, however, that by operating a plurality of relays in a circuit in such manner that the operating period of one relay overlaps that of another for a predetermined interval, the circuit may be interrupted at a rate greater than is possible by the use of a single unit alone.

With these and other objects and applications in view, my invention further consists in the arrangement and in the mode of operation hereinafter set forth and illustrated in the accompanying drawing, wherein:

Figures 1 and 2 are curve diagrams, for different operating speeds, illustrating the operating characteristics of a circuit-interrupting device such as is employed in my invention.

Fig. 3 is a similar view, illustrating the sequence of operation of a number of relays, according to my invention.

Fig. 4 is a diagrammatic view of circuits and apparatus for carrying my invention into effect, and

Fig. 5 is a top plan view of a punched tape which is shown edgewise in the preceding figure.

In order to illustrate the principles and applications of my invention, I shall describe, hereinafter, one arrangement of circuits and apparatus for carrying the same into practice, though it is to be expressly

understood that my invention is not specifically limited thereto.

The ordinary type of prior-art relay designed, particularly for operation in connection with wireless control systems, has a maximum operating speed of approximately forty words per minute. As previously pointed out, such relatively low maximum operating speed is the result of the employment of heavy, rugged relays, wherein the movable contact-bearing arms traverse relatively long paths.

Assuming radio-telegraph signals of ten-dot spaces per letter and fifty-dot spaces per word of five letters each and a speed of transmission of forty words per minute, the duration of a dot space is approximately 0.03 of a second, as indicated

by the full-line curve *a* in Fig. 1. The curve *a* shows the desired position of the relay and the curve *b* shows the actual movement of the relay. In each curve the ordinates

indicate position and the abscissæ time. The time necessary for such relay to close is approximately 0.01 of a second and the time necessary for the relay to come to rest after separation of its contacts is also approximately 0.01 of a second. Thus, the actual

time during which the relay contacts are closed is approximately 0.02 of a second, as indicated by the dotted-line curve *b* in Fig. 1.

If the same relay is operated at four times its normal speed, the relay contacts would never close, since the relay would be de-energized before the contacts would have closed,

as indicated in Fig. 2, where the full-line curve *c* illustrates the desired interval or so-called "dot-space" during which the relay contacts are to be closed and the dotted-line curve *d* illustrates the actual movement, showing the time during which the relay is energized and *d* energized.

As previously stated, I have discovered that, by employing a plurality of relays in a circuit and so operating them that the operating period of one relay overlaps that of another, a signaling system of extremely high speed may be obtained wherein the individual units operate at their normal operating speed.

In Fig. 3 is shown operating characteristic curves *e* and *f* for a pair of relays having the previously mentioned characteristics,

illustrating the overlapping sequence of op-

eration thereof, whereby signaling may be effected at a speed four times greater than is possible by the use of a single relay alone. It will be noted that the relay corresponding to curve *f* is energized, at times, while the relay corresponding to curve *e* is energized, and that the contacts of the former relay close a predetermined interval after the contacts of the latter relay open, said interval being equal to the length of a dot space, as will appear more fully hereinafter.

The system of control shown in Fig. 4 is merely one arrangement for causing a pair of relays or circuit-interrupting devices to operate in the manner indicated in Fig. 3. The system therein shown comprises a pair of parallel connected relays 1 and 2 having stationary contact elements 3, 3' and 4, 4', and co-operating movable contact elements 5 and 6, respectively, said relays being serially included in a portion 7 of a radio control system. Since the remaining portions of the control system are not essential to a clear understanding of the operation of my invention, they have been omitted. The switch units or relays 1 and 2 are primarily controlled by the relative spacings of the perforations in a pair of tapes 8 and 9, respectively, as hereinafter explained.

The unpunched tapes may be placed through an automatic punching machine of any well-known type and provided with series of punchings 11, 12, and 13, 14 for controlling the relays 1 and 2, respectively, and a series of so-called "star-wheel" punchings 15, 16. In order to illustrate the successive overlapping operation of the relays 1 and 2, as defined by the curve diagram of Fig. 3, I have shown, in Fig. 5, the tapes 8 and 9 with their several punchings arranged in the proper relative phase relation. The distance *g* and *h* separating the perforations 11 and 12 and *g'* and *h'* separating the perforations 13 and 14, illustrate the time interval between the instant when the relays 1 and 2 are energized and the instant when the relay contacts are separated, respectively.

In order to simplify the description of my invention, the mechanism for causing the operation of, say relay 1, in accordance with the perforations in the tape 8 only will be shown and described, the mechanism employed in connection with relay 2 for accomplishing this result being a mere duplication. Referring to the mechanism associated with relay 1, the tape 8 may be actuated by means of arms 17 of a star wheel 18 successively engaging said star-wheel perforations 15, the star wheel 18 being moved at a uniform speed by means of a motor (not shown). The rotative motion of the star wheel 18 may be caused to effect the oscillation of a centrally pivoted rocker arm 19 through a crank and connecting rod 21 and 22, respectively.

The rocker arm 19 is provided with a pair of pins 23 and 24 disposed upon opposite sides of the center of oscillation thereof and co-acting with arms 25 and 26 of bell-crank mechanisms 27 and 28, respectively, to cause corresponding vibration thereof. The bell-crank mechanisms 27 and 28 are pivotally mounted about the points 29 and 31, respectively. Springs 32 and 33, which are secured to arms 34 and 35 of the mechanisms, serve to maintain the arms 25 and 26 thereof in continuous engagement with their operating pins 23 and 24, respectively. The ends of the arms 25 and 26 are connected to vertically positioned rods 36 and 37 which are spaced from one another the same distance as the perforations 11 and 12 of the tape 8.

The rods 36 and 37 are of such length that, when the rocker arm 19 is vibrated by the crank 21, the ends of the rods alternately press against the lower surface of the tape 8 and extend through the respective perforations 11 when the tape is moved forward by the star wheel 18 to such position as to place a perforation directly over the end of the rod which is being actuated into contact with the tape 8. Thus, the motion of the rods 36 and 37, beyond an engagement with the lower surface of the tape 8, is determined by the relative spacing of the perforations 11 and 12. The rods 36 and 37 are normally maintained in a vertical position during non-engagement with the perforations 11 and 12 by means of spring members 36' and 37' and co-operating stop members 36'' and 37'', respectively, all as explained more fully hereinafter.

A pivotally mounted member 38 is provided with oppositely extending arms 39 and 41 perforated to removably receive the end portions of a pair of connecting links 42 and 43 extending, respectively, to the arm 34 of the mechanism 27 and to an extension 44 of the arm 35 of the mechanism 28. The pivoted member 38 carries a contact member 45 which co-acts with a stationary contact member 46. The end portions of the connecting links 42 and 43 are provided with stops 47 and 48, which are so disposed that, when the ends of the rods 36 and 37 merely engage the lower side of the tape 8, the end portions of the connecting links 42 and 43 merely move back and forth in the perforated portions of the arms 39 and 41, respectively, without disturbing the relative positions of the contact members 45 and 46.

When the tape 8 is advanced by the star wheel 18 to the position indicated in the figure and the end of the arm 37 is caused to extend through one of the perforations 11 by the force of the spring 33, the connecting link 43 is moved forward an additional amount. The additional motion of the link 43 causes the stop 48 to engage the arm 41 of the member 38 and to move the same suffi-

ciently to actuate the movable contact member or pin 45 into engagement with the stationary contact member 46, all as shown in the drawing.

- 5 When the contact members 45 and 46 are actuated into engagement, a circuit is completed through a source 49 of direct-current energy and an energizing winding 51 of the relay 1, to effect the operation thereof and 10 the closing of the portion 7 of the control circuit.

Subsequent motion of the star wheel 18 withdraws the end of the arm 37 from the perforation 11 and finally advances the tape

- 15 8 to a position where one of the perforations 12 is directly over the end of the rod 36; whereupon the rod 36 is caused to extend up through said perforation. The connecting link 42 is then moved forward an additional 20 amount, causing the stop member 47 to engage the projecting arm 39 and to move the same sufficiently to actuate the two contact members 45 and 46 out of engagement. When the two contact members 45 and 46 25 are disengaged, the energizing circuit of the relay 1 is broken and it opens to interrupt the portion 7 of the control circuit. Attention is directed to the fact that the contact members 45 and 46 remain closed during the 30 interval between the projection of the arm 37 through the perforation 11 and the projection of the arm 36 through the perforation 12.

When the tape 8 is again moved forward, 35 the operation of the star wheel 18 and the foregoing mechanical operations are repeated. Thus, it is seen that, as the tape 8 moves forward under the operation of the star wheel 18, the portion 5 of the control circuit 40 is opened and closed for a period of time proportional to the interval between the successive projections of the arms 37 and 36 through the perforations 11 and 12, respectively.

- 45 The second relay 2 may have its energizing winding 52 connected, through the energy source 49, to the relatively movable contact members 45' and 46' of a circuit-interrupting mechanism (not shown) which 50 is like that just described in connection with the relay 1. As previously stated, in order to simplify the description of my invention, such mechanism is not shown. The relative arrangement of the perforations in the two 55 tapes 8 and 9, as shown in Fig. 5, is such as to cause the operation of the relays 1 and 2 according to the predetermined sequence shown in Fig. 3.

Hence, by the operation of the relays 1 60 and 2 in the manner just described, the portion 7 of the control circuit may be opened at least four times the normal operating speed of a single relay. Further increases in the speed of interruption of the portion 65 5 of the control circuit obviously may be

effected by the addition of more relays, arranging the operating periods thereof to overlap a predetermined amount.

While I have shown but one embodiment of my invention, for the purpose of describing the same and illustrating its principles of operation, it is apparent that various changes and modifications may be made in the nature and the mode of operation and the particular mechanism employed without departing from the spirit of my invention. I desire therefore, that only such limitations shall be imposed thereon as are indicated in the appended claims or demanded by the prior art.

I claim as my invention:

1. In an electrical system, a circuit including a plurality of circuit-interrupting units and separate actuating means for each of said units said actuating means acting in combination in such manner as to cause the interruption of said circuit at a frequency greater than that obtainable by the operation of a single unit alone.

2. In a control system, the combination 90 with an electrical circuit, of a plurality of circuit-interrupting devices included therein, said devices requiring a definite time to make electrical contact and a definite time to return to their initial state after breaking 95 electrical contact, and means for causing the closing period of one device and the breaking period of another device to overlap.

3. In a control system, the combination 100 with an electrical circuit, of a plurality of switch units included in parallel in circuit therewith, said units having a definite time interval in which to open and to close, and means for causing the opening time interval 105 of one unit to overlap the closing time interval of another unit a predetermined amount.

4. In a control system, the combination 110 with an electrical circuit, of a plurality of switching units included in said circuit, said units requiring a definite time interval in which to open and to close, and means for operating said units in such manner that the operation of one switch is started prior to the discontinuance of operation of a preceding switch.

5. In a control system, the combination 115 with an electrical circuit, of a plurality of switching units included in said circuit, said units requiring a definite time interval in which to open and to close, and means for operating said units in such manner that the time interval between the successive operations of said switch units is that corresponding to the time interval during which one switch remains closed.

6. In combination, an electrical circuit, a plurality of relays the contacts of which are included therein, said relays having movable circuit-interrupting members requiring a definite time interval to close said circuit 130

and a definite time interval to come to rest after interrupting said circuit and means for securing the operation of said relays successively in such manner that said time intervals overlap.

7. In combination, an electrical circuit, a plurality of relays the contacts of which are included therein, said relays having movable circuit-interrupting members requiring definite time intervals to close said circuit and to come to rest after interrupting said circuit and means for so energizing said relays as to cause said opening time interval of one relay to overlap said closing time interval of a preceding relay by a predetermined amount.

8. In a signaling system, the combination with a circuit carrying electrical energy, of means for interrupting said circuit to form dots and dashes, said means comprising a plurality of relays having circuit-interrupting members included in parallel in said circuit and means for so energizing said relays that the operating period of one relay

overlaps that of another a predetermined amount to determine the interval between successive dots.

9. In a signaling system, a circuit carrying electrical energy to be modulated, a plurality of switching units included in said circuit, means individual to each unit for causing the operation thereof, and means for causing the operation of said units in combination in such manner that the frequency of interruption of the circuit by said combination is greater than that resulting from one single unit alone.

10. The method of signaling which consists in successively operating a plurality of circuit-interrupting units in such manner that the transient operating period of one relay overlaps that of another relay a predetermined amount.

In testimony whereof, I have hereunto subscribed my name this 25th day of November, 1922.

ARTHUR L. WILSON.
